UNITED STATES PATENT OFFICE.

EDWY O. CAPEN, OF BUFFALO, NEW YORK.

CONDENSATION-PREVENTER.

No. 845,029.

Specification of Letters Patent.

Patented Feb. 19, 1907.

Application filed January 17, 1906, Serial No. 296,563.

To all whom it may concern:

Be it known that I, EDWY O. CAPEN, a citizen of the United States, and a resident of Buffalo, Erie county, State of New York, have invented certain new and useful Improvements in Condensation-Preventers; and my preferred manner of carrying out the invention is set forth in the following full, clear, and exact description, terminating with claims particularly specifying the novelty.

This invention relates to window-ventilators, and more especially to those devices which are adapted for the prevention of condensation.

It is well known by locomotive-engineers, electric-street-car motormen, and others whose calling requires them constantly to look through a window from within a cab or the like that in cold weather moisture and frost will accumulate on the inside of the glass and render it difficult and in some cases impossible to see out.

The present invention is designed to overcome this difficulty, to which end it consists in the construction of a window-ventilator adapted to permit the entrance of small jets of cold air past the edges of the glass and to direct them across its inner surface, all as hereinafter more fully described and claimed, and as shown in the drawings, wherein—

Figure 1 is an inside elevation of the front panel of an engineer's locomotive-cab with the lower part of the inner beading removed. Figs. 2 and 3 are sections through the same on the lines 2 2 and 3 3. Fig. 4 is an inner edge view of one of the side bars of the frame with portions of the beading removed. Fig. 5 is an enlarged sectional detail of a form which may be used in some cases.

While it will be understood that this invention is useful in a variety of places, I have herein illustrated and described it as used in connection with the forward window of a locomotive-cab—that window behind which the engineer sits and through which he watches the track ahead. This window stands squarely at right angles to the line of progress and its outer side takes the impact of a strong current of air which is set up by the speed of the engine. It is manifestly essential that the glass in the window be clean and clear from frost, lest the engineer's view of the trackway be obstructed. Various devices have heretofore been contrived for preventing the accumulation of condensation on

the inner side of this and similar windows; but in the present invention the object is accomplished by admitting small jets of air around the edge of the glass and directing them across its inner face. This is accomplished as follows:

The letter F designates the frame of the window, and G the glass. The latter instead of resting against a shoulder in the frame, as usual, is held therein between outer beadings O and inner beadings I, either or both of which may be removable for the purpose of inserting or replacing the glass. By preference the outer beading is of one size throughout, and by preference the inner beading has projections P at intervals which extend a little further inward over the inner face of the glass than the remaining portion of the beading. The glass G preferably fits within the frame F, and its edges are held by contact therein; but cut into said frame at points opposite the projections are recesses R. (Best seen in Fig. 4.) The inner faces of the beadings—that is, those faces next to the glass—are cut away slightly, as at V, at points opposite said recesses R, and the cut-away portions and recesses therefore coact to produce passages for the inflow of air from next the outer face of the glass.

In use the air striking the outer face of the glass G is deflected and spread over its surface and thrown radially against the outer beading O. Entering the cut-away portions V therein, it passes around the edges of the glass through the recesses R in the frame and is directed into the cut-away portions V of the inner beading I. These cut-away portions are formed by preference under the projections P, and hence the inflowing jets of air are directed from the several edges of the glass over and across its inner face, rather than being permitted to blow toward and into the face and eyes of the engineer. It will be found in use that when the cold outside air is thus allowed to blow across the inner face of the glass no condensation or frost will form thereon, and yet the draft will not be such as will be injurious to the engineer.

In Fig. 5 is illustrated, on a somewhat larger scale, a slight variation, which I find it desirable in some cases to employ, especially where the pane of glass is quite wide or large and the distance from its edges to the center is considerable. In such cases and under some circumstances the blast of air admitted around the edges of the glass may not be

directed across its inner surface with sufficient force. In order to give more impetus to the incoming air, it will be seen in this view how the outer beading O may be cut 5 away at V' at an incline, so as to present a rather large mouth for the inlet of the outside air, also how the recess R' may be made larger and possibly rounded at its bottom to admit of the free passage of the jet of air, 10 and also how the inner beading I may have its cut-away V² tapered or undercut, so as to be larger where it communicates with the recess R' and smaller where the jet of air issues on the inner face of the glass. In practice I 15 find that this construction directs the jets with considerably more force across the inner face of the pane than the other.

What is claimed as new is—

1. A condensation-preventer consisting of 20 a pane of glass and its frame, and openings in the latter next the pane for admitting the external air which strikes the outer face of the glass and so shaped as to direct it from the sides across its inner face.
2. A condensation-preventer consisting of 25 a pane of glass, a frame surrounding its edges and having recesses at certain points next said edges, and the outer and inner beadings holding the glass in the frame and cut away 30 at points to communicate with said recesses.
3. A condensation-preventer consisting of 35 a pane of glass, a frame surrounding its edges

and having recesses at certain points next said edges, the outer and inner beadings holding the glass in the frame and cut away 35 at points to communicate with said recesses, and projections on the inner beading at the points where it is cut away, as and for the purpose set forth.

4. A condensation-preventer consisting of 40 a pane of glass, a frame within which it is fitted, means consisting of recesses at certain points for permitting the passage of the exterior air to the interior of the pane, and outer and inner beadings holding the pane in the 45 frame and cut away on those faces adjacent the pane, for the purpose set forth.

5. A condensation-preventer consisting of 50 a pane of glass, a frame within which it is fitted and having recesses at certain points 55 adjacent the edge of the glass, and inner and outer beadings holding the pane in the frame and cut away on those faces adjacent said pane, the cut-away portion of the outer beading tapering toward said recess and that of the inner beading being larger next the recess and tapering away from it.

In testimony whereof I have hereunto subscribed my signature this the 15th day of January, A. D. 1906.

EDWY O. CAPEN.
